(57) **CLAIM**

The ornamental design for a multi-positional electronic device grip and stand assembly, as shown and described.

DESCRIPTION

FIG. 1 is a front, bottom, right side perspective view of a multi-positional electronic device grip and stand assembly, showing our new design;

FIG. 2 is a rear, bottom, right side perspective view thereof;

FIG. 3 is a front elevational view thereof;

FIG. 4 is a rear elevational view thereof;

FIG. 5 is a front, right side perspective view of the multi-positional electronic device grip and stand assembly of FIG. 1, shown in a position of use;

FIG. 6 is front elevational view of the multi-positional electronic device grip and stand assembly of FIG. 1, shown with the strap portion removed for clarity of disclosure;

FIG. 7 is a front left side perspective view of the multi-positional electronic device grip and stand assembly of FIG. 1, shown in another position of use; and,

FIG. 8 is a front, left side perspective view of the multi-positional electronic device grip and stand assembly of FIG. 1, shown in yet another position of use.

The broken lines in FIG. 7 and FIG. 8 illustrate environmental subject matter that forms no part of the claimed design.
